UNITED STATES PATENT OFFICE

HERBERT S. STRAUSSER, OF CHICAGO, ILLINOIS, ASSIGNOR TO OTIS MANUFACTURING COMPANY, OF CHICAGO, ILLINOIS, A CORPORATION OF ILLINOIS

POCKET LIGHTER

Application filed July 7, 1927. Serial No. 203,911.

This invention relates to pocket lighters, and more particularly a novel ignition mechanism for lighting devices embodying a hydrocarbon saturated wick, a pyrophoric element, and a member operative to contact with the pyrophoric element to project the sparks generated by such contact toward the exposed end of the wick.

The object of the invention is to provide a dependable, positive and safe igniter for pocket lighters.

A further object of the invention is to provide a compact and convenient form of pocket lighter embodying certain novel features of construction hereinafter disclosed in connection with the accompanying drawings, in which

Figure 1 is a general view of the lighter partly in elevation and partly in section.

Figure 2 is a view in vertical section through the lighter as taken on line 2-2 of Figure 1.

Figure 3 is a perspective view of the lighter showing the manner in which the pyrophoric element is removed.

Figure 4 is a perspective view of the pyrophoric element.

Figure 5 is a detail view in section taken on the plane of line 5 of Figure 1; and

Figure 6 is a detail view of a modified form of igniter bar.

Figure 7 is a view showing the positions of the cutting disc of Figure 6.

The lighter comprises in general a metal casing of convenient shape and size for carrying in the pocket and having mounted at one end thereof the ignition mechanism presently to be described in detail. The casing is preferably formed of a thin metal shell 1 flattened on the sides and rounded at its side edges. At either end of the shell 1 are walls 2 and 3 permanently secured to the shell to form a liquid-tight casing for the hydrocarbon fuel. The lower or bottom wall 2 (considering the lighter in its upright position) is relatively thicker than the shell and is provided with a single opening therethrough located near one end and closed by a screw plug 4 flush with the bottom face thereof.

The purpose of this opening will be presently

explained. The upper end wall 3 is likewise of increased thickness and forms a base for the igniter parts, which will now be described.

Near one end of the top wall 3 is a wick mounting consisting of bushing 5 fitting into an opening through the top wall and projecting just above the top thereof. This bushing is bored axially, and fitting snugly into this bore is a sleeve 6 through which the end of a cord-like wick 7 is inserted. The upper end portion of the sleeve is enlarged to form a shoulder seating on the top of the bushing with the end of the wick projecting above the end of the sleeve. The wick 7 extends downwardly into the casing which is preferably filled with cotton or other absorbent material.

At the opposite end of the top wall 3 is a bifurcated post or standard 8 formed integral with a tubular stem 9 extended vertically downward into the casing to a point short of the bottom wall 2. The upper end portion of the stem 9 is threaded at 9^a to engage a tapped hole in the top wall 3, said post and stem being inserted and screwed down with the base of the post seating on the top wall and held in position by a lock nut 9^b on the threaded portion 9^a of the stem. Pivottally mounted on the post is a snuffer bar 10 consisting of a reduced central portion 10^a of circular cross-section and enlarged tips or ends 10^b and 10^c elongated axially and pointed at their tips. The bar 10 has an overall length slightly greater than that of the top plate so that the tip 10^b adjacent the post 8 projects substantially its full length beyond the post. Also integral with the bar 10 is a combined cam and lever arm 11 extending downwardly from the underside of the bar immediately adjacent the junction of the tip 10^b and the central portion 10^a. This arm 11 has the form of a thin web or blade projecting downwardly into the slot or bifurcation in the post 8, the bar being pivotally connected to the post by a pin 12 passing transversely through the post and the arm 11 just below the bar 10. At the opposite or free end of the bar 10 and integral with the tip 10^c is a downwardly extending cap 13 adapted to seat upon the bev-

eled edge of the bushing 5 of the wick mounting and to cover the exposed end of the wick, when the lighter is not in use.

Within the tubular stem 9 is mounted a plunger pin 14 having a rounded upper end projecting upwardly through a bore of reduced diameter at the upper end of said stem. Below the pin 14 is a coil spring 15 bearing at its upper end against a head 14^a at the lower end of the pin 14, and at its lower end against a screw plug 16 closing the lower end of the stem. The screw plug is slotted at its lower end to receive a screw driver inserted through the opening in the bottom wall 2 of the casing when its closure plug 4 is removed, it being noted that said opening is directly below the end of the stem. By adjusting the screw plug 16 the tension exerted by the spring 15 on the plunger pin 14 may be increased or decreased, and hence, in turn the pressure of said pin against the lower edge of the lever arm 11 with which it has bearing and sliding contact. As will be presently pointed out, the pressure of the plunger 14 against the edge of the lever arm 11 opposes the initial pressure exerted by the finger in operating the lighter, sufficiently to obtain the quick or snap action essential for positive ignition of the wick. To understand this action more clearly, it will be observed that in the closed position of the snuffer bar (Figure 1), the tip of the plunger is pressed upwardly against the lower extremity of the lever arm formed by two cam faces 11^a and 11^b, meeting in a point 11^c offset slightly to the left of the axis of the plunger, so that the contact is just beyond the point 11^c and against the inner cam face 11^b which is straight and inclined at an angle of about 45° to the vertical. The other or outer cam face 11^a is an arc of a circle, the center of which is eccentric to the axis of the pivot pin 12. It is to be noted also, that the axis of the plunger pin 14 is offset from the vertical line of the pivot pin 12, so that in the closed position of the snuffer bar, the plunger acts to hold the same in closed position. Hence to actuate the bar 10 downward pressure is applied on the tip 10^a thereof, with either the thumb or forefinger of the hand holding the lighter, this pressure being momentarily resisted by the plunger bearing against the cam face 11^b of the lever arm 11. Now, when the finger pressure overcomes the resistance offered by the plunger, the tip 11^c of the lever arm slides over the end of the plunger, bringing the curved cam face 11^a into contact therewith, this releasing of the lever arm by the plunger imparting the quick movement or snap.

The pyrophoric element, and the means for activating the same, will now be described: Intermediate the wick mounting and the post 8 is a fixed support for the pyrophoric element, consisting of a post 17 secured in the top wall 3 by a base portion 17^a extending

through an aperture in said wall and having its lower portion upset. The main portion of the post 17 extends upwardly above the surface of the top wall, although by preference the central portion is depressed by the formation of a recess 18 extending from the wick mounting to the post 8, as shown in Figure 3. The post 17 is moreover slotted in the direction of the groove to provide a slot 19 of a height slightly greater than the depth of the recess and slightly narrower than the width thereof. This slot forms a guide for an endwise sliding igniter bar 20 having an upturned knife edge or blade 20^a at its forward end and on the side of said post 17 adjacent the wick. The igniter bar 20 extends lengthwise of the groove 18 and beyond the post 17 in the direction of the pivoted end of the bar 10, terminating in a bifurcated arm or yoke 20^b inclined upwardly at a slight angle and having its ends flattened in a vertical plane, which straddle the depending arm 11 of the snuffer bar 10 and pivotally connected thereto near its outer edge and just above the cam face 11^a by a pin 21. Mounted on the top of the post 17 is a short tension screw 22 anchored in a tapped hole in said post and having a flat circular head 22^a with a milled or knurled edge. The post 17 also supports through the medium of the screw 22, a carrier or holder 23 for the pyrophoric element, the same consisting of a relatively flexible metal strip having a bifurcated or forked portion 23^a at one end which also straddles the lever arm 11 and is fixed on the pin 12, thus anchoring the carrier securely at one end. The tension screw 22 passes through the carrier 23 substantially midway its length, thus providing a free end portion 23^b extending toward and terminating short of the wick mounting in the form of a flat resilient strip having a downturned lip 23^c with two space notches 23^d therein. Beneath the free end portion 23^b of the carrier 23 is a thin forked plate 24 pivotally mounted at one end on the shank of the screw 22 and lying flatwise against the underside of the carrier. The forked ends of said plate form a pair of parallel spring fingers 24^a—24^b having upturned ends adapted to engage and lock within the notches 23^d in the lip of the upper strip 23. Between the free end portion of the upper strip and the plate 24 is removably held the pyrophoric element 25 (Figure 4) consisting of a small block of the pyrophoric substance, usually termed a "flint", secured to a metal base plate 25^a of slightly greater width, by means of prongs 25^b struck up from the plate and engaging around the base of the block. The pyrophoric element is inserted into the holder by swinging the carrier plate 24 outwardly at right angles, as shown in Figure 3, sliding the element endwise onto the plate with the block projecting downwardly between the fingers 24^a, and

then swinging the carrier plate forwardly again to its initial position beneath the carrier, at the same time springing the ends of the fingers into the notches 23^a to lock the "flint" in place. The swinging carrier plate 24 and the carrier 23, are held in place by means of a coil spring 26 mounted on the shank of the tension screw 22, and bearing at its lower end on the post 17, and at the upper end against the pivoted end of the carrier plate.

For filling the casing with a liquid hydrocarbon fuel, an opening for this purpose is preferably provided in one of the flat sides 15 and near the top wall. Just below the top wall 3 and in the interior of the casing is a semi-circular metal boss 27 of the same thickness as the interior of said casing, and held in place by soldering or, if desired, it can be made integral with the top wall 3. Extending transversely through the boss 27 is a large hole 27^a registering at one end with a hole in the wall 1 of the casing, thus forming a cavity which is closed by a screw plug 28 25 engaging threads adjacent the entrance to the cavity. The cavity communicates with the interior of the casing through a plurality of small radial bores 27^b drilled through the bottom of the boss forming the cavity. The screw plug 28 has a flat head 28^a with a knurled edge, the face of said screw being suitable for a monogram or initials.

Now to describe the operation of the igniting mechanism and the adjustment incident thereto: The action of the bar 10 by the downward pressure of the finger and the momentary opposition of the plunger to give positive ignition as the bar is released and thrown upwardly into substantially upright position, has already been explained. The upward movement of the end 10^c of bar 10 manifestly uncovers the wick end and at the same time actuates the reciprocating bar 20 with a correspondingly quick movement toward the exposed end of the wick. As clearly shown in Figure 1, the upturned blade 20^a at the forward end of the bar 20 has contact with the downward face of the block 25^a of pyrophoric substance, the edge of said blade 50 being beveled and slightly rounded so that on its forward stroke there occurs a cutting or scraping action, generating the sparks which are projected into the zone of the saturated wick end with a resulting ignition. In this connection, attention is directed to the fact that the cap 13 is held in positive seating contact over the wick end by the pressure exerted on the pivoted end of the snuffer bar by the spring plunger 14, to the end that a quantity of highly combustible gas is trapped in the cap. Thus when the cap is lifted the sparks are simultaneously thrown into this zone of combustion surrounding the wick, thereby insuring positive ignition. In

short, the gas is primarily ignited, which in turn ignites the wick.

In order to generate sparks in the manner described, a certain amount of pressure is required between the pyrophoric element and the blade 20^a. This is provided for by the tension screw 22 passing through the "flint" carrier. As shown in Figure 1, the carrier bears against the underside of the screw head 22^a, being yieldably held in this position by the coil spring 26. Thus by turning the tension screw downwardly, the carrier 23 is lowered until the proper contact is obtained between the blade 20^a and the pyrophoric element 25. Similarly, by releasing the tension screw, the pressure can be relieved, the spring 26 acting in an upward direction to force the pyrophoric element away from the reciprocating blade to reduce the sparking or eliminate it entirely. This tension adjustment, therefore, provides a safety device to prevent ignition should the igniting mechanism be accidentally released when in the pocket. Thus by a slight turn of the tension screw 22 in a direction to reduce the pressure, ignition is prevented even though the action is completed and while the lighter is being carried in the pocket. Likewise, a slight turn in the opposite direction restores the pressure, and the lighter will operate. To extinguish the lighted wick, it is only necessary to press the bar into closed position, as is common in lighters of this type, the cap 13 snuffing out the flame and covering the wick end until again ignited in the manner already described.

After continued use, the pyrophoric element necessarily wears down, thus requiring adjustment of the tension screw to maintain the igniting contact. In time the pyrophoric element becomes completely worn out, and a new one must be inserted. This is accomplished by swinging the carrier plate 24 to one side, as already explained and as shown in Figure 3, removing the worn element and replacing with a new one. One or more extra "flints" can be carried in the cavity formed in the casing, which is made sufficiently large for this purpose, aside from serving as a filling opening.

In Figure 6 a modified construction for the ignition bar is disclosed. In this form, the bar 30 is cylindric in shape, although operatively connected with the snuffer bar in the same manner as the one previously described. At the free end of the bar is a steel disc 31 beveled to provide a cutting edge about its periphery. The disc is loosely mounted on the bar so that it is not only free to rotate but also to tilt about its axis. The end of the bar 30 is reduced to form a bearing 30^a for the disc which is held thereon by a washer 32, the end of the reduced portion being upset to hold the washer. The bearing portion 30^a is slightly longer than the thick-

ness of the disc and a little smaller than the opening through the disc, so that there is considerable play or looseness. Moreover, the disc is beveled with the cutting edge at the forward face of the disc, that is, nearest the wick, so that as the disc is carried forward in contact with the flint, it is tilted slightly out of a plane at right angles to its path of movement, thus presenting a sharp cutting edge to the surface of the flint. During the return movement or stroke, the disc tilts at a corresponding angle in the opposite direction with the result that its contact with the surface of the flint is more nearly along the beveled portion of the edge. In this manner, the cutting or spark generating contact between the disc and the flint is confined to the forward stroke, thus reducing or eliminating the wear on the flint during the return stroke. The disc form of cutter is also desirable since it affords a longer cutting edge which is continually changed due to the rotation of the disc on its axis.

Other modifications and departures from the devices herein described may be resorted to without departing from the spirit of the invention, and therefore I do not wish to be limited except in so far as the invention is defined in the appended claims.

30 I claim as my invention:

1. An igniter comprising a base, a wick having an exposed end extending above said base, and an igniter for said wick end, comprising a snuffer bar pivoted at one end on said base and having a cap at its free end adapted to cover said wick end, an igniter bar mounted intermediate said wick end and the pivoted end of said snuffer bar and having pivotal connection at one end with said snuffer bar and provided at its opposite end with a transverse cutting edge, a post mounted on said base and slotted to form a guide for said igniter bar, a pyrophoric element carrier mounted adjacent the path of said igniter bar for contact with the edge thereof, and a tension screw anchored in said post and engaging said pyrophoric element carrier for adjusting the position of the same relative to the path of said cutting edge.

50 2. In a pocket lighter, the combination of a casing having a wick projecting therefrom, a bar fulcrumed on said casing adjacent one end and having a cap at its free end adapted to cover the end of said wick, said bar being extended beyond its fulcrum to provide an operating lever and having a cam lever extending toward said casing at right angles to said operating lever, a spring plunger mounted in said casing with its end bearing against the edge of said cam lever and acting to yieldably oppose the pressure exerted on said operating lever, and ignition mechanism mounted on said casing between said wick and said fulcrum and operatively connected with said bar adjacent said fulcrum.

3. In a pocket lighter, the combination of a casing, a wick in said casing, having its end projecting therefrom, a bar fulcrumed adjacent one end on the exterior of said casing and provided with a cap at its opposite end adapted to seat over the end of said wick, said bar being extended beyond its fulcrum to provide an operating lever and having a cam lever extending at right angles from its fulcrum toward said casing, a spring plunger mounted in said casing and adapted to bear against the edge of said cam lever at a point offset from said fulcrum in the direction of the free end of said bar said plunger acting on said cam lever to exert a yielding pressure on said bar to hold the same in closed position and to momentarily resist the movement of said bar under pressure applied to said operating lever to actuate the same, and ignition mechanism mounted on said casing and operatively connected with said bar adjacent its fulcrum.

4. In a pocket lighter, the combination of a fuel casing a wick in said casing having its end projecting therefrom, a bar fulcrumed adjacent one end on the exterior of said casing and provided with a cap at its opposite end adapted to seat over the end of said wick, said bar being prolonged beyond its fulcrum to provide an operating lever and having a cam lever extending from its fulcrum toward said casing with its edges forming cam faces meeting in a point offset from said fulcrum in the direction of the free end, a spring plunger mounted in said casing and bearing endwise against the cam face of said cam lever adjacent said point and exerting a yielding pressure on said bar to hold the same in closed position and to momentarily resist the pressure on said operating lever and ignition mechanism mounted on said casing and operatively connected with said bar adjacent its fulcrum.

5. In a pocket lighter, the combination of a fuel casing having a wick projecting therefrom, a snuffer bar fulcrumed intermediate its ends on said casing and having a cap at one end adapted to seat over the end of said wick and formed as an operating lever at its opposite end, and a cam extending from said bar towards said casing adjacent the fulcrum, a spring pressed member mounted on said casing and bearing against said cam to yieldingly oppose the pressure exerted on said operating lever, and ignition mechanism mounted on said casing adjacent said wick and operatively connected with said snuffer member.

6. In a pocket lighter, the combination of a casing having a wick projecting therefrom, a snuffer bar fulcrumed on said casing and having a cap at one end adapted to cover the end of said wick, said bar being extended at its opposite end beyond the fulcrum to provide an operating lever, and extended toward

said casing to form a cam lever, a spring plunger mounted in said casing and bearing at its end against the edge of said cam lever to yieldingly oppose the pressure exerted on said operating lever, and ignition mechanism mounted on said casing between said wick and the fulcrum of said bar, and means operatively connecting said ignition mechanism with said bar.

7. In a pocket lighter, the combination of a fuel casing having a wick projecting therefrom, a snuffer bar fulcrumed on said casing at a distance from said wick, and having a cap at one end adapted to seat over said wick, said bar being extended beyond said fulcrum at its opposite end to provide an operating lever and extended toward said casing below its fulcrum to provide a cam lever, a spring actuated plunger mounted in said casing and bearing at its end against the edge of said cam lever to yieldingly oppose the pressure exerted on said operating lever, and ignition mechanism mounted on said casing between said wick and the fulcrum of said bar, and means connecting said ignition mechanism with said bar adjacent its fulcrum.

8. In a pocket lighter, the combination of a fuel casing having a wick end projecting therefrom, a snuffer member pivotally mounted on said casing and having a portion adapted to seat over said wick end, said snuffer member being provided with a cam, a resiliently pressed member adapted to bear against said cam, said cam being shaped to oppose movement of the snuffer member from the closed position and to present an eccentric surface to the resiliently pressed member in its intermediate positions, and ignition mechanism operatively connected with said snuffer member.

Signed at Chicago, Ill., this 30th day of June, 1927.

HERBERT S. STRAUSSER.
